(57) **CLAIM**

The ornamental design for a semi-rimless metal eyeglass frame, as shown and described.

DESCRIPTION

FIG. 1 is a perspective view of an eyeglass frame showing my new design;

FIG. 2 is a front view thereof;

FIG. 3 is a rear view thereof;

FIG. 4 is a top view thereof;

FIG. 5 is a bottom view thereof; and,

FIG. 6 is a right side view thereof, the left side view being a mirror image thereof.

The broken line showing on the temples, lenses and nose pads is for illustrative purposes only and forms no part of the claimed design.
